UNITED STATES PATENT OFFICE.

JAMES PRIESTMAN, OF NEW YORK, N. Y.

HEEL-CUSHION.

SPECIFICATION forming part of Letters Patent No. 674,686, dated May 21, 1901.

Application filed September 13, 1900. Serial No. 29,978. (No model.)

To all whom it may concern:

Be it known that I, JAMES PRIESTMAN, of New York, in the county of New York and State of New York, have invented certain new and useful Improvements in Heel-Cushions, of which the following is a specification.

This invention has for its object to provide a simple device for diminishing the shock caused in walking by the heel of the shoe 10 striking the hard ground.

The invention consists in a cushion which may be applied to the heel of any shoe and which is formed of a piece of sheet metal dished in the center and supported by a continuous marginal base which rests on the heel 15 of the shoe. The heel of the foot rests on the top of the dished portion, which is nearly flat and is divided by a number of radial slits into spring-segments which, being fast to the 20 marginal base at their outer portions, yield when subjected to pressure and constitute the elastic portion of the cushion.

Of the accompanying drawings, Figure 1 represents a longitudinal section of a shoe 25 provided with my improved heel-cushion. Fig. 2 represents a plan view of the preferred form of cushion. Fig. 3 represents a side elevation of the same. Fig. 4 represents a cross-section on line 4-4 of Fig. 2. Fig. 5 represents a longitudinal section on line 5-5 of Fig. 2. Fig. 6 represents a plan view of a modified form. Fig. 7 represents a plan view 35 of my improved heel-cushion extended to provide a shank-cushion. Fig. 8 represents a section on line 8-8 of Fig. 7, showing the extended cushion in place on the heel and shank of a shoe.

The same reference characters designate the same parts in all the figures. 40 Referring to the drawings, the heel-cushion *a* is preferably formed of a piece of sheet metal cut into the shape of a shoe-heel, though it may be circular in form or of any other suitable shape. The edges of the metal plate 45 are slightly bent, all in the same direction, from the plane of the sheet, so that they form a continuous base or marginal portion *b*, which supports the cushion when it is in the proper position, whereby the central portion forms 50 a flat crown *c*, upon which rests the heel of

the foot. In my preferred form of cushion the edge *d*, which is placed nearest the toe, is straight, extending directly across the shoe from side to side, and from every part of this edge except the end portions the slope to the 55 top of the crown is the same, so that this portion of the plate presents a substantially straight elongated inclined surface. From a point approximately at the center the plate is divided by a number of radiating slits, 60 which extend nearly to the edges of the plate, into segments *e*, which are integral at their outer portions with the edges of the plate and constitute curved springs, having their free ends at that portion of the plate on which 65 rests the wearer's heel. Thus the greatest possible resiliency is given to the cushion.

In its operative position the cushion is placed in a shoe, its margin preferably resting on the inner sole. The cushion may be 70 covered by a thin piece *h* of leather or other suitable material, which serves to keep the metal from contact with the foot of the wearer.

Instead of making the cushion from a single plate I may make the spring-segments *e* 75 in separate pieces, held in their proper relative positions by a rim *j*, Fig. 6, to which they are suitably secured by rivets or otherwise.

This form of heel-cushion is very resilient 80 and does not deteriorate by wear. It also serves to ventilate the shoe, for when the springs are moved inwardly the air confined within the crown of the plate is forced out, and when pressure is removed from the cushion 85 the springs in resuming their normal positions draw air into the cavity again. In this way a flow of air is caused in the shoe at every step.

The cushion may be enameled to prevent 90 it from rusting.

In Figs. 7 and 8 I show a cushion comprising the heel-cushion above described and a shank-cushion *s*, which is preferably integral with the heel-cushion and is formed to fit the 95 shank portion of the sole immediately in advance of the heel. The cushion *s* has a series of radiating slits, forming springs, which are relatively arranged like the springs in the heel-cushion and have the same function, 100

the springs being surrounded by a continuous marginal seat or base formed to bear on the shank portion of the sole.

I claim—

- 5 1. A cushion of the character specified comprising a marginal seat or base and a series of curved springs extending inwardly from said margin and collectively constituting a resilient crowning support, the free ends of 10 the springs constituting the central portion of the support.
2. A cushion of the character specified comprising a crowning sheet-metal plate having a continuous marginal seat or base portion 15 and a series of slits radiating from the central portion of the plate toward the marginal portion, the portions of the plate between said slits constituting springs which are free at their inner ends.
- 20 3. A heel-cushion comprising a crowning

sheet-metal plate which has a depressed heel-shaped margin and a series of slits radiating from the central portion of the plate toward the margin and forming a series of springs which are free at their inner ends, the forward portion of the plate presenting a substantially straight elongated inclined surface. 25

4. A combined heel and shank cushion, comprising a heel portion and a shank portion, each having a marginal seat or base and a series of curved springs extending inwardly from said margin and constituting a resilient crowning support. 30

In testimony whereof I have affixed my signature in presence of two witnesses.

JAMES PRIESTMAN.
